EXPANSIBLE LINK CHAIN FOR A BRACELET
OR SIMILAR ARTICLE

Louis E. Valcourt, East Providence, R. I., assignor
to Kestenman Bros. Mfg. Co., Providence, R. I.,
a corporation of Rhode Island

Application March 23, 1951, Serial No. 14,607

Term of patent 7 years

(Cl. D45—4)

To all whom it may concern:

Be it known that I, Louis E. Valcourt, a citizen of the United States, residing in the town of East Providence, county of Providence, and State of Rhode Island, have invented a new, original, and ornamental Design for an Expansible Link Chain for a Bracelet or Similar Article, of which the following is a specification, reference being had to the accompanying drawing, forming a part thereof.

Fig. 1 is a top plan view of an expansible link chain showing my new design;

Fig. 2 is an edge elevational view of the link chain;

Fig. 3 is a top plan view of the link chain in expanded position; and

Fig. 4 is an enlarged top plan view of a pair of top links in the position as shown in Fig. 1.

I claim:

The ornamental design for an expansible link chain for a bracelet or similar article, as shown.

LOUIS E. VALCOURT.
